UNITED STATES PATENT OFFICE

171,659

COSTUMER DEVICE

Richard M. Neagle, Philadelphia, Pa.

Application October 21, 1953, Serial No. 27,273

Term of patent 14 years

(Cl. D33—8)

To all whom it may concern:

Be it known that I, Richard M. Neagle, a citizen of the United States, residing at 2123 Sansom Street, in the city and county of Philadelphia, Commonwealth of Pennsylvania, have invented a new, original, and ornamental Design for Costumer Device, of which the following is a specification, reference being had to the accompanying drawings, forming part thereof.

Figure 1 is a perspective view of a costumer device, showing my new design,

Figure 2 is a front elevational view of same, and

Figure 3 is a top plan view thereof.

I claim:

The ornamental design for a costumer device, substantially as shown.

RICHARD M. NEAGLE.
